UNITED STATES PATENT OFFICE.

SAMUEL D. BURKEWORTH, OF LANSING, MICHIGAN.

CLAMP.

1,127,585.

Specification of Letters Patent. Patented Feb. 8, 1915.

Application filed January 15, 1912. Serial No. 612,880.

To all whom it may concern:

Be it known that I, SAMUEL D. BURKEWORTH, a citizen of the United States, residing at Lansing, county of Ingham, State of Michigan, have invented a certain new and useful Improvement in Clamps, and declare the following to be a full, clear, and exact description of the same, such as will enable others skilled in the art to which it pertains to make and use the same, reference being had to the accompanying drawings, which form a part of this specification:

This invention relates to clamps for molds of concrete columns. It is of course designed for concrete centering but it is obvious that it may be used for other purposes.

In the drawings:—Figure 1, is a perspective, partly broken away, of one of the bars showing a wedge in place. Fig. 2, is a fragmentary section of a concrete column and a plan view of the clamp at one corner. Fig. 3, is a perspective of the mold or centering showing the clamp in place.

Heretofore clamps operating by various cam arrangements and screw arrangements have been employed for forcing the mold boards into place and holding them there. Usually four separate clamps are required for each column mold at every place along its height where a set of clamps is applied. Clamps requiring screw threads are objectionable for the reason that they are thrown around so as to jam the threads and make the clamps worthless. Clamps requiring a cam to tighten them are somewhat complicated compared with my simple arrangement. I am also aware that it has been proposed to use a set of bars such as I employ and notch them along the sides; in these notches a wedge is driven so as to draw the bars across each other and tighten them against the centering. My invention is intended as an improvement over this last-named form of clamp which is often rendered useless by reason of the teeth in the edges becoming broken by the rough usage that clamps of this character are subjected to, for clamps are very often dropped a number of stories on to solid concrete. To obviate this difficulty and do away with exposed projections which are liable to chip off, I employ the arrangement of bars and slots shown in the drawings.

Four bars *a* are employed. Each bar has a plurality of oblique slots *b* near each end.

Inasmuch as the bars are crossed at right angles the obliquity of the slots is 45°. At one end a shorter bar *c* with a raised portion is fastened by riveting, or otherwise, so to the longer bar. This is also obliquely slotted with slots that register with the slots *b* of the longer bar. Hence the plain end of the adjoining bar *c* can be slid through the space formed between the raised portion of the shorter or rider bar *c* and the longer bar *a*. The oblique slots of the plain end can be brought, as shown in Fig. 2, so they are in alignment with the slots of the adjacent bar *a* and its rider bar. By inserting a wedge *d* in one set of the overlapping slots and by driving in this wedge the overlapping bars *c* are pulled across each other so as to force them against the centering or molds. When the slots through which the wedge protrudes are brought into actual registry the wedge can not be driven any further. However, when this condition has been reached another set of slots will be found to be overlapping and another wedge can be inserted in this set and started before the first-mentioned wedge is withdrawn. By this operation continuous wedging action may be exerted upon the bars to draw them toward each other. The slots can be of considerable length; in fact almost as long as the width of the bar as they are obliquely disposed. Inasmuch as the slots may be long, it is not necessary to bring them very closely together and thereby weaken the bar so that it may be rather easily fractured. Preferably I separate the slots about one inch.

My slotted bars are believed to be a considerable improvement over the notched bars which are drawn toward each other by driving wedges into the notches. As already stated the teeth formed by the notches are susceptible to breakage while my arrangement of aligned slots which are ultimately wedged into registry are not so liable to breakage, for there are no exposed projecting portions.

The bars are temporarily held against the centering or the molds by driving nails into the wood. These nails hold the bars in place when this is necessary before the bars are tightened sufficiently against the centering to hold themselves.

The word slot is used in the specification and claims to mean a complete slot, or a fragmentary slot or recess, as it is obvious

that some of the slots could be turned into internal notches by merely cutting away the substance of the bar between adjacent slots. This, of course, would weaken the bar but 5 would in no way alter the invention which consists in locating the wedge within the outer edges of the bars and doing away with teeth on the outer edges of the bar where they are liable to be broken off.

10 What I claim is:

1. A mold clamp, having in combination a plurality of bars laid so as to present their edges to the mold and to form a complete polygon of bars, two or more of the bars 15 being laid angularly across the ends of each other, the said overlapping bars being provided each with a plurality of slots completely within the outside edges of such bar and angularly disposed with respect to the 20 axis of such bar, sets of slots of said overlapping bars being arranged to aline when the bars are at a given angularity, and one or more pairs of slots being arranged to 25 overlap, and one or more wedging pins driven into alined and overlapping slots and whose driving draws the bars across each other and across each other's longitudinal axis in the direction of the slots to 30 constrict the polygonal bar structure upon the mold.

2. A mold clamp, having in combination, a plurality of bars laid so as to present their edges to the mold and to form a complete polygon of bars, two or more of the bars 35 being laid across the ends of each other, said overlapping bars being provided each with a plurality of slots completely within the outer edges of said bar and angularly disposed with respect to the axis of

said bar, the sets of slots of said overlapping bars being arranged to aline when the bars are at a given angularity, and the said slots having also substantially parallel and continuous side walls, one or more pairs of the slots being arranged to overlap, and 45 one or more flat wedging pins driven into alined and overlapping slots and whose driving not only draws the bars across each other and across each other's longitudinal axis in the direction of the slots to 50 constrict the polygonal bar structure upon the mold, but also tends to make the bars assume pre-determined angular relations with respect to each other.

3. A mold clamp, having in combination 55 a plurality of bars forming a complete polygon of bars, the individual bars of which engage with one another at the ends by one bar passing through the end of the other bar, the said engaging ends of the 60 bars being provided each with a plurality of slots obliquely crossing the axis of each bar, the slots of the two engaging bars being arranged to aline when the bars have the given angular relation of the side walls 65 of the mold upon which the clamp is designed for use, and one or more sets of the slots being arranged to overlap, and one or more wedging pins for driving into alined and overlapping slots to draw the 70 bars across each other and constrict the polygonal bar structure upon the mold.

In testimony whereof, I sign this specification in the presence of two witnesses.

SAMUEL D. BUTTERWORTH.
